THOMAS LEWIS, OF MALDEN, MASSACHUSETTS.

Letters Patent No. 85,744, dated January 12, 1869.

IMPROVED VAGINAL INJECTION-PIPE FOR SYRINGES.

The Schedule referred to in these Letters Patent and making part of the same.

To all whom it may concern:

Be it known that I, THOMAS LEWIS, of Malden, in the county of Middlesex, and State of Massachusetts, have invented an Improved Vaginal Injection-Pipe to Syringes, of which the following is a full, clear, and exact description, reference being had to the accompanying drawings, making part of this specification, in which—

Figure 1 is a perspective view of the pipe.

Figure 2 is a sectional view of the pipe.

Figure 3, end view of the pipe, showing perforations.

This device has been suggested to me by the lack of perfect action in the ordinary vaginal injection-pipes to syringes.

When using the common vaginal injection-pipes to syringes, the walls of the vagina hug so closely to the pipe as really to defeat the purposes to which the injection is applied, for sufficient room is not given to allow of any play to be given to the jets of fluid from the injection-pipe; and when the pipe is within the vagina, the fluid is continually escaping, without accomplishing the purpose of the injection, either in cleansing the vagina or otherwise.

Now, my improved vaginal injection-pipe, being made in the shape it is, distends the walls of the vagina when inserted, and, as the perforations are located, allows a free play to the jets when forced through the pipe into the vagina, and the bulb so fills the vagina as to prevent the fluid from escaping as fast as injected. Thus I succeed in obtaining the whole benefit which may result from a vaginal injection.

In the drawings, which are made on an enlarged scale—

A is the pipe.

B, the head or bulb-end, which is inserted into the vagina.

C shows the perforations for jets of fluid.

It will be noticed that all perforations are forward of the points *e d*. This is to allow the bulb to distend the walls of the vagina, to give full force to the fluid-jets forced through the perforations.

This improved pipe is adapted to the use of any kind of syringe, but I prefer to use it with that class of enema-syringes provided with an elastic bulb, operating in connection with valves placed within the metallic connections of the syringe, and to an improvement in which I obtained Letters Patent of the United States, September 10, 1867.

What I claim as my invention, and desire to secure by Letters Patent, is—

Device B, for a vaginal injection-pipe, with perforations C C, forward of line *e d*, substantially as and for the purposes set forth.

In testimony whereof, I have signed my name to this specification, in the presence of two subscribing witnesses.

THOMAS LEWIS.
